UNITED STATES PATENT OFFICE.

WILLIAM K. BAYLESS AND THOMAS B. BAYLESS, OF LEXINGTON, KENTUCKY.

CLOTH-MEASURING DEVICE.

No. 879,846.

Specification of Letters Patent.

Patented Feb. 25, 1908.

Application filed September 24, 1906. Serial No. 336,083.

To all whom it may concern:

Be it known that we, WILLIAM K. BAYLESS and THOMAS B. BAYLESS, citizens of the United States, residing at Lexington, in the county of Fayette and State of Kentucky, have invented certain new and useful Improvements in Cloth-Measuring Devices; and we do hereby declare the following to be a full, clear, and exact description of the invention, such as will enable others skilled in the art to which it appertains to make and use the same.

This invention is a tape-measure provided with reversely arranged measures on its opposite sides, and intended to be rolled in bolts of cloth, ribbon or other fabric that is sold by the yard, so that when the cloth is unrolled from the bolt a corresponding length of tape will go with it. As so arranged, the device performs two functions: First, it enables the clerk or salesman, when selling goods to a customer, to cut off the desired length or number of yards without resort to a yard-stick or any separate measure, and prevents him from liability of making mistakes; and, second, the tape indicates the amount of goods in the bolt, as well as the amount cut off, so that the merchant can at any time take stock of his goods and make an inventory without having to unroll the broken bolts to find how much is left in them, since the measure tells him exactly. The tape also serves as an advertising medium, since the advertisement of the manufacturer or the merchant or both may appear on every yard of goods sold, such advertisement being printed upon the tape which is cut off and sold with the goods.

In the accompanying drawings, which form a part of this specification: Figure 1 represents a fragment of a tape-measure embodying my invention, showing about a quarter of a yard of the upper or obverse side; that is the side which appears as the tape is unrolled with the goods. Fig. 2 shows the reverse or under side of the same. Fig. 3 represents, on a reduced scale, the obverse or upper side of such tape-measure six feet in length, this length being taken merely as an example. Fig. 4 shows the reverse or under side of the same. Fig. 5 is a perspective view of a bolt of cloth, having such a tape-measure rolled therewith, a portion of the cloth to-

gether with a corresponding length of the tape being shown unrolled from the bolt.

As observed from the drawings, the tape is provided with corresponding units of measure on both sides, but with their respective denominations reading in reverse directions. In other words, the measure on the upper or obverse side reads from right to left, or oppositely to the reading of an ordinary rule; while the measure on the under or reverse side reads from left to right. The division lines on one side are respectively in registration with those on the opposite side, being only reversely denominated. Thus, in a six foot tape, the division line indicating 1 ft. on the obverse side would correspond with the division line indicating 5 ft. on the reverse side.

Each measure, that is the obverse as well as the reverse side of the tape, is divided into feet and inches, as well as into yards and quarter and half yards. The denominations for the foot divisions increase in regular order, so that the measure reads consecutively 1 ft., 2 ft., 3 ft., 4 ft., and so on, according to the length of the tape. On the other hand, the yards are not indicated by increasing digits, but each yard is denoted by the symbol "1 yd.", or indicia to the same effect; while the quarter and half yards are also indicated, thus, $\frac{1}{4}$ yd., $\frac{1}{2}$ yd., and $\frac{3}{4}$ yd. The foot and yard divisions are, moreover, preferably designated by distinguishing indicia; for example, the denominating symbols for the foot divisions may be printed in black, while the denominating symbols for the yards, quarter and half yards are printed in larger type and in red, or in such other manner as to readily distinguish the yard divisions and fractional yard divisions from the foot divisions. Thus each side of the tape provides a succession of clearly indicated one yard measures; and is also divided into feet numbered consecutively. On both the obverse and reverse sides, the symbols or indicia of the various units are preferably located at the left of the respective division lines, as shown. The tape thus described is rolled in or with the bolt of cloth, spool of ribbon, or other roll of goods to be sold by the yard, as represented in Fig. 5, in such manner that when a portion of the cloth is unrolled from the bolt an equal amount of tape will go with

it; it being understood that the tape is commensurate in length with that of the cloth. In selling to a customer, the cloth is most conveniently and therefore most frequently taken from the bolt in the manner shown in Fig. 5; that is the cloth is unrolled from the bolt toward the right, or the bolt itself is rolled from the end of the cloth toward the left, enabling the salesman to cut off the desired length at the right-hand side of the bolt. For this reason, the tape is so arranged in the bolt that its obverse side, or side which appears uppermost when the cloth is unrolled, reads from right to left, so as to provide a measure running from the free end of the cloth toward the bolt, and denominated in like manner. The under or reverse side of the tape can be gummed so as to stick or adhere more or less to the cloth; but in any event the tape will be unrolled measure for measure with the cloth, its obverse side appearing uppermost and its reverse side lying upon the cloth. As thus arranged, it is evident that the obverse side of the tape provides upon the surface of the goods itself a succession of yard measures, whereby the salesman can readily cut off one yard, two yards or any number of yards without resort to a yard-stick or other separate measuring device, and without liability of error, the cloth being self-measured so to speak. At the same time, the reverse or under side of the tape, which if stuck can readily be pulled from the surface of the goods and turned over for inspection, indicates the number of feet of cloth in the bolt.

The tape is cut off with the goods. For example, if a yard of cloth is sold, a yard of tape goes with it; and every such yard may bear an appropriate advertisement of the manufacturer or retailer or both. When any portion of goods is cut off, the succeeding yard-measure on the obverse side of the tape is left intact, together with the last figure or indicia on the division line on which the cloth was cut, since, as aforesaid, such figure is located at the left of said division line. This figure, which is of course at the end of the tape, indicates the number of feet of cloth that have been cut off from the bolt. In the same manner, the last figure on the reverse or under side, which is also left intact, indicates the number of feet of cloth remaining in the bolt. Thus the tape, besides furnishing an ever-ready succession of yard-measures on the face of the cloth, shows at all times the number of feet left in the bolt, as well as the number of feet cut off, the addition of which gives the original length of the bolt. The merchant can take stock or make an inventory at any time without the necessity of unrolling his broken bolts.

Of course either side of the tape may be the obverse side by reversing the tape end for

end. For example, the reverse side of the tape shown in the drawing may become the obverse side, and vice versa, by turning the tape over and placing what is shown as the outer end at the inner end or center of the bolt. This is obvious by reason of the fact that one side of the tape is practically a reversal of the opposite side. Also, the tape may be formed or arranged for or in a left-handed bolt as well as a right-handed bolt. By a left-handed bolt, I mean one from which the cloth is unrolled toward the left, or in which the bolt itself is rolled toward the right from the free end of the cloth, as distinguished from a right-handed bolt, the latter being represented in Fig. 5. In the case of a left-handed bolt, the obverse or upper side of the tape would have its denominations reading from left to right, and the reverse or under side would read from right to left. The tape shown in the drawings may be utilized for a left-handed bolt by turning it over and placing what now appears as the free end in the center of the bolt; or practically reversing the tape end for end. Inasmuch, however, as the bolt of cloth would usually be unrolled in the manner of Fig. 5, it is well to designate which shall be the obverse or upper side of the tape, and which end shall be rolled in the bolt first. This may easily be done by an appropriate mark or symbol at the inner end of the tape, so as to enable the manufacturer to incorporate the appropriate end in the bolt, and have the obverse and reverse sides of the tape reading in the manner heretofore indicated with respect to the free end of the cloth when unrolled from the bolt.

The tape may be made of paper, cloth or any suitable material, and of any desired width and length commensurate with the cloth; and it may be of any desired color or colors and printed in any appropriate manner.

We are aware that tape-measures adapted for incorporation in packaged fabrics are not new, nor is it broadly novel to provide such measures with scales reading in reverse directions, hence we make no broad claim thereto.

What we claim as our invention is:

A tape-measure designed to be rolled into a bolt of material and being of a length commensurate with that of the latter, said measure having upon its obverse or exposed face linear graduations indicating feet, yards and fractions of yards, the yard graduations being designated by like denominating symbols throughout the length of the tape and the foot graduations being numbered consecutively in progressively increasing ratio from the outer to the inner end of the tape to disclose the amount of material sold, the yard and foot denominating symbols being of a distinctively contrasting nature, said tape

having on its reverse or normally concealed face linear graduations identical in character and arrangement with the first named graduations but to read in relatively reverse order with the foot graduations numbered in progressively increasing ratio from the inner to the outer end of the tape for disclosing the amount of material remaining in the bolt and adapting the tape, by end-wise reversal, to be disposed with either face uppermost in

the operation of incorporating the same in the bolt.

In testimony whereof we affix our signatures, in presence of two witnesses.

Correction in Letters Patent No. 879,846.

It is hereby certified that in Letters Patent No. 879,846, granted February 25, 1908, upon the application of William K. Bayless and Thomas B. Bayless, of Lexington, Kentucky, for an improvement in "Cloth-Measuring Devices," an error appears in the printed specification requiring correction, as follows: In line 88, page 2, the word "center" should read *inner end*; and that the said Letters Patent should be read with this correction therein that the same may conform to the record of the case in the Patent Office.

Signed and sealed this 17th day of March, A. D., 1908.

[SEAL.]

C. C. BILLINGS,
Acting Commissioner of Patents.

having on its reverse or normally concealed face linear graduations identical in character and arrangement with the first named graduations but to read in relatively reverse order with the foot graduations numbered in progressively increasing ratio from the inner to the outer end of the tape for disclosing the amount of material remaining in the bolt and adapting the tape, by end-wise reversal, to be disposed with either face uppermost in

the operation of incorporating the same in the bolt.

In testimony whereof we affix our signatures, in presence of two witnesses.
